UNITED STATES PATENT OFFICE.

GUSTAF HELLSTRÖM, OF KINGSWAY, LONDON, ENGLAND.

SUCTION-ROLL.

1,234,543.

Specification of Letters Patent. Patented July 24, 1917.

Application filed April 23, 1917. Serial No. 163,984.

To all whom it may concern:

Be it known that I, GUSTAF HELLSTRÖM, a subject of the King of Sweden, residing at Kingsway, in the county of London, England, have invented Improvements in Suction-Rolls, of which the following is a specification.

This invention relates to that kind of suction roll for paper making machines, 10 drying machines, pulp vats and similar apparatus, wherein a suction box is used in conjunction with such a suction roll for the extraction of water from the paper, or pulp, or felt sheet or web, or sheet or web 15 of other material (hereinafter included in the term wet sheet).

The present invention has for its object to prevent or minimize clogging of the perforations in the periphery of the suction cylinder by fibers or the like that may be drawn 20 into them by suction from the wet sheet and thus to enable the suction effect to act in a more continuous uniform and advantageous manner than heretofore for removing 25 water from the wet sheet.

For this purpose, the suction effect is caused to take place through opposite portions of the perforated cylindrical wall of the suction roll (hereinafter referred to for 30 brevity as the roll wall) and the intermediate interior of the roll and thence through a suction box arranged external to and bearing against the outer surface of the roll wall at a portion thereof that is, for the time being, opposite to the portion thereof over 35 which the wet sheet extends, so that, as the roll rotates, liquid will be drawn from the wet sheet in an inward direction through a portion of the roll wall into the interior of the roll and in an outward direction from 40 the interior of the roll through the roll wall opposite the suction box. Those portions of the roll wall that are not covered either by the wet sheet or by the suction box are 45 shut off from the interior of the roll and the suction box by means, such as stationary dividing off or separation walls, arranged within the roll and fitting against the inner surface thereof in an air tight manner, so 50 that the suction effect can only take place through the portions of the roll wall covered by the wet sheet and the suction box. The stationary separating walls may with advantage be arranged to form open boxes or 55 chambers preferably in communication with the external atmosphere.

In the accompanying drawing, Figure 1 shows in vertical transverse section and Fig. 2 in central longitudinal section, a suction roll arrangement according to the invention. 60

In this example, 1 is the suction roll having a perforated periphery and 2 is one of the two end bearings for the roll. 3 is the wet sheet which passes over the roll and from which water is to be extracted. 65 Rollers 4 and 5 serve to guide the wet sheet at the points where it meets and leaves the suction roll. The perforations 1^a in the roll wall may be of inwardly tapering shape, and are covered by a perforated mantle 6 of suitable metal, for example copper. 70

7 is a stationary suction box arranged at the lower part of the suction roll. This box opens toward the roll and is in communication through a pipe 8 with a suction air pump 8^a and is provided with a pipe 9 to conduct away the extracted water. A fluid tight joint is produced between the suction box and the roll by suitable packing means, such, for example, as packing bars 10 arranged to slide in grooves in the side walls of the box and pressed against the suction roll by springs 11. 75

A stationary pipe 13 that passes in an air tight manner through the end walls of the 85 suction roll and through the center of the roll, carries by means of hollow arms 13^a, two dividing off boxes or chambers 14 and 15 which are open toward the inner surface of the suction roll between the parts of the 90 roll covered by the wet sheet and suction box and bear in a fluid tight manner against the inner surface of the roll in the same way as the suction box 7 bears against the outer surface of the roll. The boxes 14 and 15 are 95 in communication with the external atmosphere through the hollow arms 13^a and the central pipe 13. At the same time, air can enter the said boxes through that part of the roll wall opposite the said boxes, so that at 100 such parts atmospheric pressure prevails at both sides of the roll wall. As the boxes 14 and 15 cover those portions of the surface of the suction roll which are neither covered by the wet sheet 3 nor by the suction box 7, 105 it is evident that air and water can only be drawn into the roll by suction through that part of the roll covered by the wet sheet.

Arranged at each end of and within the suction roll is a movable annular cover 16 110 that is carried by a disk 16^a and is adjustable longitudinally, as by screws 17 operated

from the outside and extending in an air tight manner through the adjacent end wall of the roll. By moving the covers longitudinally so as to cover a smaller or greater part 5 of the perforated wall of the roll, the roll, can be readily adapted to treat wet sheets of different widths.

The action of the improved suction roll arrangement is as follows:—

- 10 When air is sucked through the pipe 8 and a partial vacuum thereby created in the suction box 7 and in the interior of the suction roll 1, water will be sucked out of the wet sheet 3 covering the upper part of 15 the roll, such water passing through the perforations in the mantle 6 and in the roll wall into the interior of the roll and thence through the perforations in the opposite portions of the roll wall into the suction box 20 7 from which it is discharged by the pipe 9. The discharge is preferably suitably regulated by a valve 9^a so as to maintain a certain water level in the suction box. At the same time the two boxes 14 and 15 prevent 25 any air from being sucked into the roll through those parts thereof which are neither covered by the wet sheet 3 nor by the suction box 7. It is obvious that when water is sucked from the wet sheet, some 30 fibers may pass through the perforated mantle 6 and enter the small holes in the wall of the suction roll. As the roll turns, and as the water is extracted from the inside toward the outside by the suction box 7, the 35 water will wash out any fibers which may have entered the holes and in this way render the roll self-cleaning, which is of great importance.

The suction roll can be used either in combination with a pressure roll 19 or not, as may be desired.

What I claim is:—

1. The combination with a suction roll and means for leading a wet sheet from 45 which liquid is to be extracted, over and partly around a portion of the perforated cylindrical wall of said roll, of a suction box arranged external to said roll and in fluid tight connection with the outer surface of 50 another portion of the perforated wall of said roll and means located within said roll adapted to close communication between the suction box and the external atmosphere through those portions of the perforated roll 55 wall not covered by the wet sheet under treatment and the suction box.

2. The combination with a suction roll, means for leading a wet sheet on to a portion of the perforated wall of said roll and 60 means for leading the sheet away from said roll, of a stationary external suction box opening toward another portion of the perforated roll wall, means adapted to make a fluid tight joint between said suction box and roll, means for drawing air from said 65 suction box, and the interior of said roll, means for leading away liquid from said suction box, stationary boxes constituting separation walls, within said roll, said boxes opening toward and fitting in a fluid tight manner 115 against the inner surface of the perforated roll wall and covering at the inside the parts thereof not covered at the outside by the wet sheet being treated and the suction box and means for placing said boxes in 120 communication with the external atmosphere through the end walls of said roll.

suction box and the interior of said roll, means for leading away liquid from said suction box and means within said roll closing communication between said suction box and the atmosphere through those portions 70 of the perforated roll wall not covered by the wet sheet and suction box.

3. The combination with a suction roll, means for leading a wet sheet on to a portion of the perforated wall of said roll and 75 means for leading the sheet away from said roll, of a stationary external suction box opening toward another portion of the perforated roll wall, means adapted to make a fluid tight joint between said suction box 80 and roll, means for drawing air from said suction box and the interior of said roll, means for leading away liquid from said suction box and stationary separation walls, arranged within said roll and covering those 85 portions of the perforated roll wall not covered by the wet sheet and suction box.

4. The combination with a suction roll, means for leading a wet sheet on to a portion of the perforated wall of said roll and 90 means for leading the sheet away from said roll, of a stationary external suction box opening toward another portion of the perforated roll wall, means adapted to make a fluid tight joint between said suction box 95 and roll, means for drawing air from said suction box and the interior of said roll, means for leading away liquid from said suction box and stationary boxes constituting separation walls, within said roll, 100 said boxes opening toward and fitting in a fluid tight manner against the inner surface of the perforated roll wall and covering at the inside the parts thereof not covered at the outside by the wet sheet being treated 105 and the suction box.

5. The combination with a suction roll, means for leading a wet sheet on to a portion of the perforated wall of said roll and means for leading the sheet away from said roll, of a stationary external suction box opening toward another portion of the perforated roll wall, means adapted to make a fluid tight joint between said suction box and roll, means for drawing air from said suction box, and the interior of said roll, means for leading away liquid from said suction box, stationary boxes constituting separation walls, within said roll, said boxes opening toward and fitting in a fluid tight manner 115 against the inner surface of the perforated roll wall and covering at the inside the parts thereof not covered at the outside by the wet sheet being treated and the suction box and means for placing said boxes in 120 communication with the external atmosphere through the end walls of said roll.

6. The combination with a suction roll, means for leading a wet sheet on to a portion of the perforated wall of said roll and 125 130 means for drawing air from said

- means for leading the sheet away from said roll, of a stationary external suction box opening toward another portion of the perforated roll wall, means adapted to make a fluid tight joint between said suction box and roll, means for drawing air from said suction box and the interior of said roll, means for leading away liquid from said suction box, a stationary pipe extending centrally through said roll and its end walls, hollow arms fixed to said pipe, boxes carried by said arms and opening toward the inner surface of said roll and means for effecting air tight joints between said boxes and the inner surface of said roll, said boxes being arranged opposite those parts of the roll wall that are between the parts thereof covered by the wet sheet under treatment and the suction box and in communication with the external atmosphere through said arms and pipe and through the perforated roll wall opposite which they are arranged.
7. The combination with a suction roll and means for leading a wet sheet from which liquid is to be extracted, over and partly around a portion of the perforated cylindrical wall of said roll, of a suction box arranged external to said roll and in fluid tight connection with the outer surface of another portion of the perforated wall of said roll, means located within said roll adapted to close communication between the suction box and the external atmosphere through those portions of the perforated roll wall not covered by the wet sheet under treatment and the suction box, and endwise adjustable means adapted to mask the perforations in portions of roll wall.
8. The combination with a suction roll and means for leading a wet sheet from which liquid is to be extracted, over and partly around a portion of the perforated cylindrical wall of said roll, of a suction box arranged external to said roll and in fluid tight connection with the outer surface of another portion of the perforated wall of said roll, means located within said roll adapted to close communication between the suction box and the external atmosphere through those portions of the perforated roll wall not covered by the wet sheet under treatment and the suction box, and longitudinally adjustable annular covers arranged to slide within the end portions of said roll and mask perforations in the roll wall.
